UNITED STATES PATENT OFFICE.

ROBERT A. FORESMAN, OF ESSINGTON, PENNSYLVANIA, ASSIGNOR TO WESTINGHOUSE ELECTRIC AND MANUFACTURING COMPANY, A CORPORATION OF PENNSYLVANIA.

TUYÈRE CONSTRUCTION FOR STOKERS.

Application filed July 15, 1920. Serial No. 396,377.

To all whom it may concern:

Be it known that I, ROBERT A. FORESMAN, a citizen of the United States, and a resident of Essington, in the county of Delaware and 5 State of Pennsylvania, have invented a new and useful Improvement in Tuyère Construction for Stokers, of which the following is a specification.

This invention relates to mechanical stokers of the underfeed type wherein the fuel is supplied to the grate through retorts, and more particularly to the grate surface and tuyères thereof, and has for an object the production of side tuyères adapted to facilitate combustion of the fuel adjacent the side walls of the furnace and at the same time prevent the formation of objectionable clinkers.

Where the usual form of side tuyères is employed, the side walls of the furnace are unprotected from the intense heat adjacent the surface of the burning fuel, and consequently clinkers adhere to the heated side walls and accumulate so as to interfere with 20 the combustion of the fuel issuing from the side retorts unless they are regularly removed. Such clinkers are usually dislodged from the side walls by means of rams or pokers inserted through poke holes in the 25 sides of the furnace. As it is necessary to forcibly jar the clinkers free from the walls by repeated ramming movements of the poker, permanent injury is done to the fire brick walls which necessitate shutting down 30 the furnace for repairs.

By replacing the usual flat side tuyères with high tuyères which slope from a point adjacent the wall to the near side wall of the adjacent retort, the fuel is prevented from 40 coming into contact with the fire brick. The tuyères are constantly cooled by the air passing through them, and clinkers do not adhere thereto.

Another object of the invention is the production of side tuyères having the characteristics described above which may be economically and simply constructed and which may be readily assembled or replaced.

Another object is the production of side tuyères having the above described characteristics which may be applied to standard stokers employing flat stepped side tuyères, and which may receive air from the usual side tuyère box and uniformly distribute it to the fuel resting against the tuyères.

Another object is the production of side tuyères having ample cooling surfaces and facilities whereby overheating, warping, and cracking are prevented.

These and other objects are attained by 60 means of a stoker construction embodying the features herein described and illustrated in the accompanying drawing forming a part hereof, wherein:—

Fig. 1 is a longitudinal-vertical section of 65 an underfeed stoker taken through the center of a retort showing a side wall equipped with the improved side tuyères; Fig. 2, a transverse section on the line II—II of Fig. 1; Fig. 3, a vertical transverse section 70 through a side tuyère shown in Figs. 1 and 2; Fig. 4, a rear elevation of a modified form of side tuyère plate; Fig. 5 a transverse section through the tuyère plate shown in Fig. 4 taken on line V—V of Fig. 4; Fig. 6 75 is a view in section taken on line VI—VI of Fig. 3; and Fig. 7 is a sectional view taken on line VII—VII of Fig. 3.

Referring to the drawings, I have shown the improved form of side tuyères applied 80 to a well known type of underfeed stoker, but it will be understood that the side tuyères may be used effectively in stokers of other types. The stoker illustrated includes a fuel hopper 5 disposed adjacent the 85 front wall 6 of the furnace and aligned with a fuel retort 7 which is adapted to receive the fuel forced from the hopper by the reciprocating ram 8.

In the furnace illustrated, a plurality of 90 retorts are employed which extend longitudinally of the furnace in parallel relation, and rows of tuyère plates 9 are arranged in stepped relation between the retorts. Fuel is forced out of the retorts by the incoming fuel and spreads out over the tuyères in a well known manner. Each retort is formed of a pair of spaced support members 10 which are connected by means of a bottom plate 11. The supports 10 of 100 adjacent retorts are spaced apart so as to form a tuyère box 12 which is in open communication with the air box 13 beneath the retorts. Tuyère plates 9 are supported upon the flanged upper edges of the supports 10 in stepped relation, and air is delivered from the tuyère box to the fuel bed through tuyère openings 13' provided in the top and bottom faces of the tuyère blocks or plates. 105 Heretofore stokers have been equipped 110

with side tuyères similar in profile to the tuyères located between the retorts, such side tuyères being supported upon a side tuyère box 12' formed by a side support 10' and a support 10 of the adjacent retort. Such tuyères do not prevent the fuel from coming into contact with the side walls of the furnace, and consequently clinkers form thereon in the manner previously described.

In order to obviate this difficulty, I have provided side tuyères 15 disposed between the side retort 7 and the furnace side wall 16 and adapted to be mounted upon the standard supports 10' and 10. These tuyères form, in effect, a continuation of one side of the side retort and project above the normal level of the fuel bed adjacent the side wall so as to prevent the hot fuel from coming in contact with the side wall.

As shown in Figs. 2 and 3, each side tuyère includes a rear or back-plate 17 adapted to fit snugly against the side wall 16 and rest upon the upper flange of the support member 10', and a front or tuyère plate 18 which rests upon the support member 10 of the side retort and is inclined toward the side wall. The upper flanges of the supports 10' and 10 are provided with notches 19' and 19 into which portions of the plates 17 and 18 fit respectively so as to prevent the plates from moving longitudinally of the supports. The lower extremities of the plates 17 and 18 are provided with flanges 20' and 20 which project under the upper flanges of the supports 10' and 10, respectively, the flanges serving to hold the plates 17 and 18 against vertical displacement.

The tuyère plates 18 form, in effect, a continuation of the retort side wall and are spaced from the back-plates 17 so as to provide an air chamber 21 into which air passes from the tuyère box 12' to the inlet space 22 provided between the lower edges of the plates. The air is discharged to the fuel adjacent the tuyère plates through a series of tuyère openings 23 distributed over the face of the plates and adapted to direct the air into the fuel bed. The tuyère openings may be of any suitable form, but are preferably elongated as shown in Fig. 4.

In order to prevent excessive preheating of the air passing to the upper portion of the tuyères in order that the temperature of that section may be maintained relatively low by the cooling action of the air, each tuyère plate is provided with an integral diaphragm 24 extending upward from the bottom of the plate to a point substantially midway between the top and bottom thereof. Air entering the chamber 21 must pass to the top of the tuyère before it is delivered to the opening in the lower portion thereof. The diaphragm serves also as a heat conducting or cooling flange or web.

The cooling action of the air supplied to the tuyères is sufficient to prevent excessive heating of the tuyères and thus prevents the formation of clinkers which cannot accumulate upon the cool surface thereof. Referring to Fig. 3, it will be seen that tuyère plate 18 is provided with webs 25 which serve as stiffening and heat conducting webs.

In Figs. 4 and 5 I have illustrated a modified form of tuyère plate 18' which is similar to the plate just described with the exception that the heat conducting and cooling members comprise a series of inwardly projecting conical lugs 26 around which the air circulates before passing through the tuyère openings 23'. A variety of forms of cooling surfaces may be employed without departing from the spirit of the invention.

While I have described and illustrated but two embodiments of my invention, it will be apparent to those skilled in the art that various changes, modifications, additions, and omissions may be made in the apparatus without departing from the spirit and scope of the invention as set forth by the appended claims.

What I claim is:

1. In a stoker for furnaces, the combination of support members defining a furnace side-wall air box adapted to receive air under pressure and having opposed horizontal flanges with notched portions, a back-plate supported by the support member adjacent the furnace side-wall and having depending flanges extending beneath the notched portions of its support member, and a tuyère plate having depending flanges at its lower edge extending beneath the notched portions of its supporting member flange and having its upper side resting against the upper side of the back-plate.

2. In a stoker for furnaces, the combination of support members defining a furnace side wall air box adapted to receive air under pressure and having opposed horizontal flanges with notched portions, a back plate supported by the support member adjacent the furnace side wall and having depending flanges extending beneath the notched portions of its support member, and a tuyère plate having depending flanges at its lower edge extending beneath the notched portions of its supporting member flange and having its upper side resting against the upper side of its back plate, said tuyère plate having inwardly extending members for increasing the radiating surface thereof.

3. In a stoker for furnaces, the combination of support members defining a furnace side wall air box adapted to receive air under pressure and having opposed horizontal flanges with notched portions, a back plate supported by the support member adjacent the furnace side wall and having depending

flanges extending beneath the notched portions of its support member, a tuyère plate having depending flanges at its lower edge extending beneath the notched portions of its supporting member flange and having its upper side resting against the upper side of the back plate, and a baffle plate extending upwardly parallel to the tuyère plate.

4. In a stoker for furnaces, the combination of support members defining a furnace side wall air box adapted to receive air under pressure and having opposed horizontal flanges with notched portions, a back plate supported by the support member adjacent the furnace side wall and having depending

flanges extending beneath the notched portions of its support member, a tuyère plate having depending flanges at its lower edge extending beneath the notched portions of its supporting member flange and having its upper side resting against the upper side of the back plate, a baffle plate extending upwardly substantially parallel to the tuyère plate, and ribs connecting said baffle plate and tuyère plate. ²⁰

In testimony whereof, I have hereunto subscribed my name this 12 day of July, 1920. ²⁵

R. A. FORESMAN.
